CLAIM

I claim the ornamental design for a food and beverage tray, as shown and described.

DESCRIPTION

FIG. 1 is a top plan view of a food and beverage tray;

FIG. 2 is a bottom plan view thereof;

FIG. 3 is a front elevation view thereof;

FIG. 4 is a side elevation view thereof; and,

FIG. 5 is a perspective view of a food and beverage tray taken from the front, top and right.

The appearance of the rear of the food and beverage tray is a mirror image of the front of the food and beverage tray. The appearance of the right side of the food and beverage tray is a mirror image of the left side of the food and beverage tray.

The broken-line portions of the figures indicate additional features of an embodiment of the food and beverage tray, but form no part of the claimed design.
